DESIGN FOR A SHOE

Jacob A. Izenstatt, Roxbury, Mass., assignor to Jay Shoe Manufacturing Company, Marlboro,
Mass.

Application February 5, 1935, Serial No. 55,253

Term of patent 3½ years

To all whom it may concern:

Be it known that I, Jacob A. Izenstatt, a citizen of the United States, residing at 159 Ruthven Street, Roxbury, in the county of Suffolk and State of Massachusetts, have invented a new, original, and ornamental Design for Shoes, of which the following is a specification, reference being had to the accompanying drawing, forming part thereof, in which:—

Fig. 1 is a side perspective view of a shoe showing my new design; and

Fig. 2 is a plan view of the same.

I claim:

The ornamental design for a shoe as shown.
In witness whereof I hereby affix my hand.

JACOB A. IZENSTATT.
